(54) **STEAM ENGINE, CIRCULATING**

(76) Inventor: **Timothy Beach**

*Timothy Beach,
Letters Patent.*

The Schedule referred to in these Letters Patent and making part of the same containing a description in the words of the said Timothy Brack himself of his improvement, being an Elementary circulating Steam Engine.

This machine is for the purpose of raising a column of water by steam, which water in its descent gives motion to a wheel or any other body to be connected to any machinery requiring this motion to be continued, and is produced in the following manner: viz a boiler is to be constructed at any convenient height to be filled and fed by a pump connected with the boiler, and which may be worked by levers connected to the main shaft, or otherwise at one end of the boiler is a valve, etc to ascertain the proper height of the water on the opposite end are inserted as many horizontal tubes as may be thought proper, which tubes at a small distance from the boiler have a stop cock, which may be worked by the machine so constructed as to let on the steam to one tube whilst it cuts it off from the other, and in like manner for as many tubes as may be used. These tubes descend through a cistern of water, and as they rise again at the opposite end have two valves so constructed as to open one inwards to receive the water of the cistern, the other to open to cut off the communication when necessary and permit the water to ascend the tube. The tubes continue to rise until of the height required and then bend down in such a manner as to discharge the water drawn through them into a cistern which water is to be let full upon the wheel or other body to be set in motion. From this cistern a small pipe conveys water to the pump to feed the boiler. The operation of the machine is carried on in the following manner: viz. The steam when generated in the boiler is passed through the stop cock into the tubes, when it descends towards the valves, it is forced by a body of water drawn through the valve opening inwards, and which water is immediately upwards through a valve, also under the water in the cistern continuing of the cistern to be forced upon the body wheel to be set in motion. What I claim as my particular invention and for which I desire a patent is the application of steam in the manner above described to raising a column of water which in its descent is to give motion to machinery.

SIR:

The printed copies
of Patent No. 70,000, Beck,
are exhausted.

As soon as printed a copy will be mailed you to complete your order.

By direction of the Commissioner:

Very respectfully,

Chief Clerk.
